UNITED STATES PATENT OFFICE.

ROY E. COLE, OF DETROIT, MICHIGAN, ASSIGNOR TO LIBERTY MOTOR CAR COMPANY,
OF DETROIT, MICHIGAN, A CORPORATION OF MICHIGAN.

DESIGN FOR A LAMP-FRONT FRAME.

53,673.

Specification for Design.

Patented Aug. 5, 1919.

Application filed May 17, 1919. Serial No. 297,965. Term of patent 14 years.

To all whom it may concern:

Be it known that I, ROY E. COLE, a citizen of the United States of America, residing at Detroit, in the county of Wayne and State of Michigan, have invented a certain new, original, and ornamental Design for a Lamp-Front Frame, of which the following is a specification, reference being had therein to the accompanying drawings, forming part thereof, in which—

Figure 1 is front elevational view of a lamp front frame, showing my new design; and Fig. 2 is a side elevation thereof.

I claim:

The ornamental design for a lamp front frame substantially as shown.

ROY E. COLE.
